UNITED STATES PATENT OFFICE.

ALEXANDER GUSTAV THEODOR RIPBERGER, OF DRESDEN, SAXONY,
GERMANY.

PROCESS OF PRESERVING FOOD.

SPECIFICATION forming part of Letters Patent No. 317,673, dated May 12, 1885.

Application filed March 2, 1885. (No specimens.)

To all whom it may concern:

Be it known that I, ALEXANDER GUSTAV THEODOR RIPBERGER, of Dresden, in the Kingdom of Saxony, Germany, have invented 5 certain new and useful Improvements in the Preservation of Provisions, &c., of which the following is a specification.

Difficulty is experienced in protecting great bulks of provisions—such as for military or 10 naval or other purposes—against injurious influences for a long period, even if such provisions consist of thoroughly baked and comparatively dry goods. Moisture, deposit and spreading of fungi, spores, microbes, calandre, 15 and other vermin are known to be destructive to provisions. Endeavors have been made to protect the provisions during storage, either by the hermetical exclusion of air or by manual treatment—that is to say, by taking the 20 provisions out of the boxes or other receptacles, and to dust or clean them, thereby counteracting, periodically, the injurious influences. There are hardly any energetic and reliable 25 means known or in use by which vermin, out side or inside of the provisions, are entirely removed; at the same time, hardly any means are known that afford perfect security against vermin, moisture, &c., affecting the provisions.

The present invention consists in providing 30 means for effecting the above specified object. The method employed, according to this invention, consists, in the first instance, not to hermetically exclude the air from the provisions, but to provide means for the air to reach 35 the provisions in a filtered state or condition; and in the second instance, to use the filter employed within the walls of the receptacles as a protection against the approach of vermin, &c., by impregnating such filter and walls 40 with certain substances. It is to be understood that neither the ingredients for such impregnation, nor the method in which it is applied, will prove injurious to the provisions.

In using this method, the receptacle for provisions—that is to say, sacks, casks, boxes, or 45 barrels, of wood or tin—is lined inside with a layer of fibers. I prefer to use cotton-wool for this purpose, and to impregnate the cotton-wool with a liquor, as hereinafter specified. 50 This application of a layer of impregnated cotton-wool is done by means of double sacks, if

sacks are the receptacles employed for the provisions. If boxes, casks, &c., are employed, the layer of the impregnated cotton-wool is put on the inside of the receptacle, and is 55 thereafter covered by means of coarse fabric or pasteboard or glazed board or veneer.

All receptacles made of wood will offer ready access to the air by means of the joints, which generally increase in width during storage. If the joints in such receptacles are 60 very close or tight, holes may be bored into top, bottom, or sides of such receptacles. If such receptacles are made of tin or other metal, the walls, tops or bottoms may be suitably 65 pierced, all such holes or joints being covered inside by the above-mentioned inside filtering-layer. If baked provisions are packed for storage in a warm condition or state, and a change of temperature takes place within the receptacles by cooling or otherwise, the outer air will 70 enter into the receptacle; but this outer air, which would carry the destructive germ to the provisions in the form of fungi, spores, microbes, &c., will be perfectly filtered by means 75 of the layer of cotton-wool, and will only come in contact with the provisions in its filtered state. The impregnation of the cotton-wool layer and of the material used for constructing the receptacles will furthermore prevent the caterpillar of the *Tinca granella*, and mites (known 80 as the worst enemies of military and naval provisions) will not penetrate the impregnated layers. As all these insects and all sorts of coarse vermin have a disgust or aversion 85 against bitter substances and salt, I prefer to choose an impregnating liquor composed of such substances. I take ten parts of castor-leaves, (*folia ricini*), ten parts of laurel leaves, (*folia lauri*), ten parts of three-leaf 90 leaves, (*folia trifolia*), five parts of green walnut-shell, (*corticis nucum juglandii*), five parts of gentian root, (*Radix gentianae*), cut the same and extract them by one hundred and fifty parts of water, which is poured on boiling, and 95 which is allowed to extract in a closed vessel during about an hour. This extract is afterward filtered through woolen bags, and then fifteen parts of common salt are dissolved in it. This liquor I use at a temperature of about 50° 100 centigrade (122° Fahrenheit) to impregnate the cotton-wool layer, which shall be used as the

filtering medium, or to impregnate sackcloth or ready-made sacks, of which I prefer those without seams. The surplus liquor is removed by passing the cotton or cloth or sacks through 5 a wringing machine, and they are afterward dried.

The material used—such as wood—for constructing the receptacles is impregnated by immersing it in the liquor at about 50° centi-grade (122° Fahrenheit) or by treating it with 10 the said liquor by means of one of the well-known impregnating methods. Carriages for transport, or wood for building up temporary storage-houses, will be sufficiently treated by 15 a double wash with the boiling liquor.

In dressing sacks for the above-mentioned purpose—that is to say, to make them suitable for receiving provisions—I proceed as follows: The impregnated sack is lined inside 20 by a layer of impregnated cotton-wool of about three-fourths of an inch thick, and a second sack, not impregnated and preferably without seams, is inserted into the lined outer sack. It may be well to stitch these three layers together, but it may suffice to stitch the layer of 25 impregnated cotton-wool to the outer or to the inner sack, or to attach it thereto in any suitable way. The inside sack is made so much shorter at top that the outer sack with the 30 cotton-wool layer will suffice to effect the closure of the sack, for which purpose I prefer to use a short cylinder of wood, impregnated in the liquor and covered with impregnated cotton-wool. Against this cylinder the top of the 35 outer sack with its layer of cotton-wool is bound, and I prefer to provide a sufficiently deep horizontal groove in the wood cylinder into which groove the folds of the outer sack will be lodged if the sack is closed by string or other suitable means. The provisions inclosed in this 40 sack will be protected against all named outer injurious influences.

In using boxes, casks, or other wooden receptacles, I proceed by covering the inside of 45 the walls (sides, top, and bottom) with a layer of impregnated cotton-wool, this layer being fastened to the walls by a diluted solution of glue. This cotton-wool layer I afterward 50 cover by pasteboard, glazed board, sackcloths, or veneer, which are fastened by nails or any other suitable means. The parts of the cover forming the closing joint receive layers of 55 impregnated cotton-wool only, so that in closing the receptacle cotton will join on cotton.

In storing baked provisions for military, naval, or other purposes, I recommend to store 60 them in the receptacle while still in a warm condition, and immediately thereafter to close the receptacles, in order to withdraw the provisions immediately after leaving the oven as

quick as possible from the influence of the atmosphere.

In using carriages for transport, which are fitted out in the above-described manner, I recommend to provide all joining or closing 65 faces with tongue and groove, and to insert a loose plait of impregnated cotton-wool into the groove. In these carriages the loose cooled provisions—such as bread, biscuit, lard, &c.—are tightly stored, and the cover of the carriage 70 is closed by wedges, bars, or turn-buckle.

Although in the foregoing description the new method of packing and storing has been described as especially employed for military and naval provisions, it is obvious that nearly 75 all other other eatables, seeds, grains, and grocers' and druggists' ware may be permanently preserved and stored in the described manner against any outer injurious influences.

Although the above-named substances for 80 producing the impregnating liquor have proved to give good results, the use of other organic bitter substances is not excluded, and may be used without departing from the main feature of this invention.

There is no necessity for handling the provisions during any period or length of storage, therefore there will be no loss by breakage, &c.

The receptacles may be closely stored, therefore, in a given space. In using the above-described method of packing, larger quantities may be stored than heretofore.

This method will insure for army and navy 90 thoroughly healthy and nice provisions.

I do not claim inclosing the provisions to be preserved in cotton cloth, cotton-wool, sawdust, or other substances saturated with a preservative compound, such as described in English Patent No. 6,134 of 1882.

I claim as my invention—

The method specified for protecting provisions of all kinds during storage against the noxious or injurious influence of moisture and against the intrusion of vegetable or animal 105 organism by storing such eatables or provisions without the hermetical exclusion of air, in sacks, boxes, or other receptacles lined with a layer of a filtering medium—such as cotton-wool—impregnated with a bitter extract and salt, and the material of such receptacles being also impregnated with such bitter 110 substances and salt, substantially as specified.

In testimony that I claim the foregoing as my invention I have signed my name in presence of two subscribing witnesses.

ALEXANDER GUSTAV THEODOR RIPBERGER.
